US00D843635S

(12) **United States Design Patent** (10) **Patent No.:** **US D843,635 S**
Van Egmond (45) **Date of Patent:** **** Mar. 19, 2019**

(54) **SOLAR POWERED LAMP**

(71) Applicant: **Antoinetta Jacoba Hendrika Van Egmond**, Bussum (NL)

(72) Inventor: **Antoinetta Jacoba Hendrika Van Egmond**, Bussum (NL)

(**) Term: **15 Years**

(21) Appl. No.: **29/564,439**

(22) Filed: **May 12, 2016**

(30) **Foreign Application Priority Data**

Nov. 12, 2015 (EM) 002857292-0002

(51) **LOC (11) Cl.** **26-05**

(52) **U.S. Cl.**

USPC **D26/96; D26/51**

(58) **Field of Classification Search**

USPC D26/46, 49, 36, 74, 22, 71, 91, 96, 130,
D26/40-41, 50-51, 123-124, 1-2, 4-6,
D26/148-149; 320/110; D13/180;
362/33, 612, 555

CPC H01M 2/022; F21Y 2115/10; F21L 4/00;
F21L 4/08

See application file for complete search history.

(57) **CLAIM**

The ornamental design for a solar powered lamp, as shown and described.

DESCRIPTION

A portion of the disclosure of this patent document contains material, which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever. The copyrighted material contained in the disclosure applies to the whole design depicted in the drawings. FIG. 1 is a perspective view of the solar powered lamp; FIG. 2 is a frontal view of the solar powered lamp; FIG. 3 is a back view of the solar powered lamp; FIG. 4 is a side view of the solar powered lamp; FIG. 5 is a top view of the solar powered lamp; and, FIG. 6 is a bottom view of the solar powered lamp. The broken lines, shown in the drawings, represent portions of the article which form no part of the claimed design.

1 Claim, 6 Drawing Sheets
